UNITED STATES PATENT OFFICE.

FRED C. AREY, OF OAK PARK, ILLINOIS, ASSIGNOR TO EDGAR AMES TURNER, OF CHICAGO, ILLINOIS.

PROCESS OF MAKING EXPANDED RIBBED METAL LATHS.

1,318,952.

Specification of Letters Patent.

Patented Oct. 14, 1919.

Application filed October 2, 1916. Serial No. 123,226.

To all whom it may concern:

Be it known that I, FRED C. AREY, a citizen of the United States, residing at Oak Park, county of Cook, State of Illinois, have 5 invented a certain new and useful Improvement in Processes of Making Expanded Ribbed Metal Laths, and declare the following to be a full, clear, and exact description of the same, such as will enable others 10 skilled in the art to which it pertains to make and use the same, reference being had to the accompanying drawings, which form a part of this specification.

My invention has for its object to produce 15 a simple and efficient method of rapidly transforming a metal strip into a sheet of expanded metal having open mesh lying between solid or unexpanded portions.

A further object of my invention is to 20 produce a simple and novel method of expanding a slitted panel lying between unslitted portions, in such a way that there is no displacement of the unslitted portions relatively to each other in the lengthwise 25 direction; thus avoiding the formation of irregularly shaped ends on a sheet comprising a series of panels separated by unslitted portions.

The various features of novelty whereby 30 my invention is characterized will hereinafter be pointed out with particularity in the claim; but, for a full understanding of my invention and of its objects and advantages, reference may be had to the following detailed description taken in connection 35 with the accompanying drawing, wherein:

Figure 1 is a top plan view, more or less diagrammatic, of a strip in the various stages of transformation between the plain 40 slitted condition and the finished product;

Fig. 2 is a side or edge view of the sheet or strip shown in Fig. 1;

Fig. 3 is a section taken on line 3-3 of Fig. 1 on a somewhat larger scale than Fig. 1;

Fig. 4 is a section taken on line 4-4 of Fig. 1;

Fig. 5 is a section taken on line 5-5 of Fig. 1;

Fig. 6 is a section taken on line 6-6 of Fig. 1;

Fig. 7 is a section taken on line 7-7 of Fig. 1;

Fig. 8 is a section taken on line 8-8 of Fig. 1;

Fig. 9 is a top plan view of one panel of a strip or sheet slitted preparatory to the expanding process;

Fig. 10 is a top plan view of a fragment of a single panel completely expanded and ribbed; and

Fig. 11 is a longitudinal section on an enlarged scale showing a somewhat different way of stretching the strands from that illustrated in the other figures.

In accordance with my invention, I slit a strip or sheet of sheet metal along lines parallel with the side edges in the manner now commonly employed in making diamond mesh expanded metal. The slitting is done in panels lying between solid or unslitted portions which are adapted to be formed into ribs. While my method may be employed to expand a sheet comprising only a single panel it will ordinarily be employed in connection with wide strips or sheets containing a series of panels so as to produce integral sheets of expanded metal made up of comparatively narrow expanded panels separated from each other by ribs. In the arrangement shown in Fig. 1 there are two slitted panels, 1 and 2, between which is an unslitted portion or band, 3, while at the edges of the strip are similar unslitted portions, 4 and 5. In order to expand a sheet of this kind so as to transform the slitted panels into diamond mesh, it is necessary either to stretch the strands of the slitted portions or to reduce the length of the unslitted portions, because the mere expansion of the slitted material results in a shortening of the same. In accordance with my invention I stretch the strands before the expanding process begins so as to give them the necessary length to permit the sheet or strip to be expanded without buckling the unslitted portions. This may conveniently be accomplished by rolling or pressing the slitted panels in such a way that the strands are bowed out of the plane of the sheet, being elongated in the bowing or bending operation. This can be done in various ways. Thus, by referring to the enlarged view, Fig. 9, it will be seen that the slits are arranged in broken lines so that each individual slit as indicated at 6, for example, overlaps the adjacent ends of two slits in the next row, as indicated at 7 and 8, for example. This produces transverse rows of what may be termed key

pieces, 9, each of which, in the expanded metal, forms one of the apexes or corners of a diamond. I prefer to stretch the metal by forcing alternate rows of key pieces out of the plane of the sheet, leaving the remaining rows undisturbed. Thus consecutive sections of each panel may be forced as a whole toward the same side of the sheet as indicated at 10 in Figs. 1 and 2 or some portions may be pushed out from one side of the sheet and others from opposite sides as indicated at 11 and 12 in Fig. 11. The extent to which the displacement of the material out of the normal plane of the sheet is carried is just great enough so to elongate the strands that when the sheet is expanded and the panels transformed into diamond mesh, the expansion is allowed to take place by a mere bending of the strands and without additional stretching; thus making the process of expanding simple and easy and avoiding an uneven distribution of stresses which might result in tearing the expanded fabric.

25 The expansion of the entire sheet is preferably accomplished progressively. Thus, after the strands have been stretched, one of the outermost bands or unslitted portions is gradually forced laterally out of the 30 plane of the sheet until finally it has been carried far enough to open the strands whereupon it will be allowed to remain in a plane at one side of and parallel with the main portion of the sheet. As soon as the 35 advance end of the first panel has been expanded as heretofore explained, the second unslitted band is forced laterally, expanding the second panel and laying the first panel flat. The third band or unslitted portion 40 is then pressed laterally, bringing the expanded portion of the second panel into the same plane as the expanded portion of the first panel. In this way, one panel after another will be expanded until the strip or 45 sheet is transformed into a sheet comprising panels of diamond mesh separated by unslitted bands.

In the arrangement illustrated, the band, 4, is the bounding member of the panel, 1, which is to be expanded first. From the point marked 12 in the drawings to the point marked 13, the band, 4, gradually inclines away from the plane of the sheet. As the points 12 and 13 are carried toward

the left, a progressive expansion takes place. 55
The deflection of the band or rib member, 3, may begin just opposite the point 13, as at 14; the intention being to permit the advance section of the first panel to be completely expanded before expansion of the 60 second panel begins. The deflection of the member 3 continues to a point, 15, separated from the point 14 a distance equal to the distance between the points 12 and 13; the points 13 and 15 lying in a plane parallel 65 with the plane of the unexpanded portion of the sheet. The deflection of the rib member 5 begins at a point, 16, which may be just opposite the point 15 and continues to a point, 17, which is at a distance from the 70 point 16 equal to the distance between the points 12 and 13. At the point 13 the panel 1 has been completely expanded as illustrated in Fig. 5, but lies at an angle to the panel 2. At the point 15 the panel 1 has 75 been laid flat while the panel 2 has been expanded but lies at the same angle as that at which the panel 1 lies at the point 13. At the point 17, as indicated in Fig. 7, the panel 2 has been laid in the same plane as 80 the panel 1.

After the expansion has been completed, the bands or rib members, 3, 4 and 5, are pressed or rolled into U-shaped or V-shaped troughs or ribs, as indicated at 80, 40 and 50 in Fig. 8. The parts are preferably so proportioned that the finished sheet as shown in Fig. 8 has approximately the same width as the sheet shown in Fig. 7, the process of bending the members 3, 4 and 5 into ribs and thus decreasing the width thereof in the plane of the sheet, causing the expanded panels to be given a final stretch or set. 85 90

I claim: 95
The method of producing expanded sheet metal which consists in forming in a sheet slitted panels, alternating with unslitted portions, stretching the strands of the slitted panels to elongate them, and then expanding the sheet by progressively deflecting each unslitted portion out of the normal plane of the sheet and on the same side of 100 said plane.

In testimony whereof, I sign this specification. 105

FRED C. AREY.
